CLAIM

The ornamental design for a tablet case with keyboard, as shown and described.

DESCRIPTION

FIG. 1 is a first perspective view of a tablet case with keyboard showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a view of the tablet case with keyboard in a used state; and,

FIG. 10 is an enlarged view of the area marked "10" in FIG. 1.

The broken lines in the drawings depict portions of the tablet case with keyboard that form no part of the claimed design.

1 Claim, 10 Drawing Sheets
